OLE HVINEUDE, OF MILWAUKEE, WISCONSIN, ASSIGNOR TO OUTBOARD MOTORS CORPORATION, OF MILWAUKEE, WISCONSIN, A CORPORATION OF MICHIGAN

OUTBOARD MOTOR DRIVE SHAFT HOUSING ASSEMBLY

Application filed February 28, 1932. Serial No. 584,594.

This invention relates to improvements in outboard motor drive shaft housing assemblies.

It is the object of the invention to provide a novel and improved assembly in which the ordinary tubular shaft housing of an outboard motor may be externally reinforced by means serving a functional purpose in the operation of the motor. More particularly 10 stated, I propose to employ a water pipe, on the outside of the shaft housing, as a compression or tension member for the transmission of propeller thrust in high powered devices.

15 In the drawing:

Figure 1 is a vertical axial section through the shaft housing and lower unit assembly of an outboard motor device embodying the invention.

20 Figure 2 is a view similar to Fig. 1 showing a modified application of the reinforcing element where the design requires that it be subject to compression rather than tension.

Figure 3 is a detail in cross section in the plane indicated at 3—3 in Fig. 1.

Figure 4 is a fragmentary front elevation of the parts shown in Fig. 2.

Like parts are identified by the same reference characters throughout the several views.

25 The lower units 5 in Fig. 1 and 5' in Figs. 2 and 4 are made to house the usual gearing for connecting the engine drive shaft 6 with the shaft carrying propeller 7. In the construction shown in Fig. 1 the lower unit has a rearwardly disposed water inlet scoop 8, while in the device shown in Fig. 2 the water inlet comprises a hole 9 in the center of the leading edge of the lower unit housing. In each instance a water passage formed within 30 the lower unit leads upwardly to its upper end.

35 The shaft housing shown at 10 in Fig. 1 and 10' in Fig. 2 comprises a casting of generally tubular form provided at its upper and lower ends with enlarged heads 11 (and 11') and 12 (and 12'). The primary function of these castings is to provide for connection of the shaft housing member with other component parts of the outboard motor structure 40 but, additionally, the heads provide anchor-

age means for a reinforcing strut which may be subjected to compression or to tension as required to fit the design of a particular outboard motor.

The upper head 11 or 11' contains a water 55 chamber 15 with an outlet at 16. The inlet to the water chamber is through a threaded opening at 17 disposed either at the front or rear of the shaft housing proper, as may be required. 60

The lower head 12 or 12' has an opening 65 communicating with the water passage in the lower unit. This opening is preferably unthreaded. In the Fig. 1 construction the opening 18 leads to a counterbore 19 of increased cross section with which the water passage 20 of the lower unit directly communicates. In the Fig. 2 construction one of the bolts 21, whereby the shaft housing and lower unit are secured together, is made 70 hollow. Its head constitutes, in effect, a portion of the head 12' of the shaft housing for the purpose of receiving thrust as hereinafter to be described. It has a counterbore 23 of a large diameter which communicates with 75 the passage 22 leading through the bolt and to the water conduit 24 in the lower unit.

The part 25 constitutes not only a water 80 pipe, but also a structural reinforcing member. In each of the alternative devices here- in disclosed it is screw threaded into the opening 17 in the upper head 11 or 11'. In each instance its lower end is received into the lower head 12 or 12' in an organization which provides for relative adjustment whereby the 85 pipe 25 may be subjected to tension or pressure. In each instance the pipe 25 carries a nut 26 threaded to it at its lower end.

In the Fig. 1 construction pipe 25 is located at the rear of the shaft housing proper. 90 Consequently, the forces to which it will be subject when the propeller 7 is in operation, will be tension forces. Accordingly, the nut 26 is disposed in the enlarged counterbore 19 and seats from below against the head 12 95 of shaft housing 10 to subject pipe 25 to tension. The pipe is movable through the bore 18 to accommodate this tensioning adjustment.

In the Fig. 2 construction the pipe 25 is 100

located at the front of the shaft housing where it will be subjected to compression when the propeller 7 is in operation. Accordingly, the nut 26 is disposed on the upper side of the 5 lower head 12' of the shaft housing in a position where it may be turned down against the head of the hollow bolt 21 to exert thrust on the shaft housing and thereby to subject pipe 25 to compression.

10 In the particular design herein disclosed there is no threaded connection between pipe 25 and either of the lower head portions 12 or 12'. Hence the thrust of the nut itself is relied upon to provide a water-tight joint between the pipe 25 and the lower end of the shaft housing. No gaskets are illustrated in the drawing for the reason that the use of gaskets where required is obvious.

It is to be observed that the form of the 20 device is such that it does not require any substantial modification of the contours which the shaft housing would have in any event. Both the upper and lower terminal portions of the shaft housing are united with 25 adjacent outboard motor parts in the same manner as if the reinforcing pipe 25 were not employed. Yet the pipe virtually gives the shaft housing the form of a truss and greatly reinforces its strength as compared 30 with the strength of other shaft housings which do not have this feature. The invention is particularly valuable as applied to high powered and particularly high speed outboard motors.

35 I claim:

1. An outboard motor drive shaft housing comprising a tubular shaft housing member provided with upper and lower anchorage means offset in a forward and rearward plane, 40 and a reinforcing element connecting said upper and lower anchorage means and provided with means subjecting it to a force opposing the direction in which propeller thrust acts thereon.

45 2. An outboard motor drive shaft housing comprising spaced vertically extending members rigidly connected together at one end and adjustably connected in re-enforcing engagement at the other.

50 3. An outboard motor drive shaft column comprising a member adapted to extend longitudinally of an outboard motor engine drive shaft for the connection of bearings in which said drive shaft operates, and a reinforcing element connected to exert at 55 spaced points of said member a force opposing the force to which said member is subject in the operation of said drive shaft.

55 4. In an outboard motor structure, means 80 for supporting the lower unit comprising a pair of tubular members, and means providing rigid connection between said members at longitudinally spaced points, one of said members being adjustably fixed to exert a 85 force upon the other.

5. In an outboard motor structure, the combination with a tubular shaft housing, of a water pipe connected externally with said shaft housing at its respective ends, provided with means for introducing a bracing stress 70 therein, and comprising means for reinforcing the shaft housing.

6. In an outboard motor structure, the combination with a tubular shaft housing having an offset chamber providing an anchorage, of a water pipe connected with said anchorage and communicating therethrough with said chamber, and means adjustably connecting said water pipe at its other end with said shaft housing.

7. In an outboard motor structure, a mounting for a lower unit comprising a pair of tubes, and means rigidly connecting said tubes at their respective ends in side by side positions, one of said tubes being relatively 85 variable in length with respect to the other and provided with means for fixing its adjustment as to length whereby to subject the other to pressure.

8. In an outboard motor structure, the combination with a tubular shaft housing provided with a water chamber having a threaded anchorage portion offset from such shaft housing, of a water pipe in threaded engagement with said anchorage portion, and a nut threaded to the opposite end of said water pipe and in thrust bearing relation to a portion of said shaft housing.

9. In an outboard motor structure, the combination with a tubular shaft housing having upper and lower heads, of a reinforcing water pipe rigidly connected with one of said heads and adjustable with respect to the other.

10. In an outboard motor structure, the combination with a tubular shaft housing having upper and lower heads, of a reinforcing water pipe rigidly connected with one of said heads and adjustable with respect to the other, said pipe bearing a nut engageable with the head with respect to which it is adjustable.

11. In an outboard motor structure, the combination with a tubular shaft housing having upper and lower heads, of a reinforcing water pipe rigidly connected with one of said heads and adjustable with respect to the other, said pipe bearing a nut engageable with the head with respect to which it is adjustable at the side remote from the body of said pipe, whereby to subject said pipe to tension.

12. In an outboard motor structure, the combination with a tubular shaft housing having upper and lower heads, of a reinforcing water pipe rigidly connected with one of said heads and adjustable with respect to the other, said pipe bearing a nut engageable with the head with respect to which it is adjustable, and said nut being turnable to 120

ward the end of said pipe in effecting thrust toward said housing whereby to subject said pipe to compression.

13. An outboard motor structure comprising a tubular shaft housing and a water pipe applied externally thereto and including means subjecting said pipe to tension, said pipe being so positioned with respect to said shaft housing that the tension thereof will 10 oppose propeller thrust on said housing.

14. In an outboard motor structure, the combination with a shaft housing, of a water pipe connected therewith at its ends, and means for adjusting said pipe to maintain it 15 under compression, said pipe being so disposed with reference to said shaft housing that the compression thereof will exert on the shaft housing a force opposed to propeller thrust thereon.

20 15. An outboard motor column comprising a truss formed of spaced substantially vertical stress bearing members rigidly connected at their ends, one of said members being adjustable in length to introduce a bracing 25 stress therein, and one of said members being hollow and comprising a shaft housing.

16. An outboard motor column comprising a truss formed of substantially vertical spaced stress bearing members, rigidly connected together at their ends, one of said 30 members being hollow and comprising a water pipe, and means for adjusting the effective length of one of said members to introduce a bracing stress therein.

35 17. An outboard motor column comprising a truss formed of substantially vertical spaced stress bearing members rigidly connected together at their ends, means for adjusting the effective length of one of said 40 members to introduce a bracing stress therein, said members being hollow and one serving as a shaft housing while the other serves as a water pipe.
